(57) **CLAIM**

The ornamental design for an escalator inlet, as shown and described.

DESCRIPTION

FIG. 1 is a perspective view of an escalator inlet according to a first embodiment of our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is a top-left perspective view thereof;

FIG. 9 is a top-right perspective view thereof;

FIG. 10 is a front-perspective view of an escalator inlet according to a second embodiment of our new design;

FIG. 11 is an additional perspective view thereof; and,

FIG. 12 is an additional perspective view thereof.

The broken lines in the drawings show portions of the escalator inlet which form no part of the claimed design. Conventional shading is illustrated for purposes of highlighting the line drawings, but forms no part of the claimed design.

Any combination of the illustrated features, including claimed features and unclaimed features, may be claimed in this application or a continuing application claiming priority to this application by converting any portion of the broken lines to solid lines, any portion of the solid lines to broken lines, or both.
